UNITED STATES PATENT OFFICE

DORSEY F. ASBURY, OF BROOMES ISLAND, MARYLAND

RADIO APPARATUS

Application filed February 19, 1926. Serial No. 89,443.

My invention relates to radio apparatus and has particular reference to improvements in tuning units, my purpose being to provide a tuning unit including parts having two movements relative to one another effective individually to change the tuning status of the unit, together with means to cause said movements to be produced simultaneously and to vary the amounts thereof relative to one another, whereby a plurality of such units, when connected together for collective operation, may be caused to tune simultaneously and accurately with different wave lengths, thereby eliminating the necessity of more than once individually adjusting the units and departing from arrangements heretofore proposed by me in my applications 683,756 and 80,833 for example, in which means for accomplishing the same general purpose is included in operating means for tuning units of conventional types rather than in the tuning units themselves, the latter arrangement being advantageous for various reasons among which may be mentioned the ease with which any desired plurality of units may be connected together for collective operation, the relative cheapness and ease of manufacture, and simplicity, compactness and durability in construction.

My inventive idea is capable of embodiment in different mechanical structures, certain of which are illustrated in the accompanying drawings, but it is to be understood that the structures shown are merely intended to disclose the essential features and novel characteristics of my invention in certain preferred forms and that its scope is as defined in the appended claims.

In the drawings, wherein like characters of reference denote corresponding parts in the different views:—

Fig. 1 is a side elevation illustrating a preferred embodiment of my invention in which a plurality of tuning units are arranged abreast and combined in a unitary structure; Fig. 2, a top plan view; Fig. 3, an end elevation; Fig. 4, a side elevation illustrating a modified form of my invention;

Fig. 5, a top plan view of the structure shown in Fig. 4;

Fig. 6, a transverse section on the line 6—6 of Fig. 4;

Fig. 7, a transverse section on the line 7—7 of Fig. 4; and

Fig. 8, an elevation of one of the bendable cam members used in both the preferred and modified form of my invention.

Referring to the drawings in detail, first to Figures 1 to 3 inclusive, it will be observed that the tuning units are in the form of variable plate condensers and that two of them are embodied in a unitary structure. It is to be understood, however, that my improvements are applicable to any other form of tuning unit in which the parts thereof have a plurality of movements relative to one another to effect tuning of the unit, being applicable to coils for example, and that although two units have been shown embodied in a single structure, this number may be increased without limit, or, if desired, each unit may be formed separate from other units and as many individual units as desired may be connected together for collective operation. The single structure, two unit arrangement illustrated is preferred, however, for the reason that certain parts essential to a single unit may be made to serve in a dual capacity in a two unit structure.

In the arrangement illustrated a block 10 serves as a base or support for the various parts of the tuning units, said block having rigidly secured to each side thereof, by means of bolts or other fasteners 12, spaced capacity plates 14, said bolts or fasteners also serving to secure rigidly to said block a pair of arms 16 which arms extend in spaced relation beyond one end of said block and have rotatably mounted therein a shaft 18, said shaft having fixed thereto a member 20 to which are pivoted as at 22 two sets of spaced capacity plates 24 movable bodily into different overlapping or interdigitating relations with respect to the two sets of plates 14, respectively, by swinging movement of said member 20.

Also rigidly secured to each side of block 10 is a bar 26 having threaded therein at

relatively closely spaced intervals a plurality of screws 28, each set of said screws adjustably supporting a bendable cam strip 30. Each set of plates 24 carries a roller 32, which 5 rollers rest, respectively, upon cam strips 30 whereby the latter serve to support the portions of plates 24 remote from their pivotal connections 22 with member 20, the result being that when shaft 18 is rotated to swing member 20 the two sets of plates 24 are moved bodily in one direction by said member and pivotally in another direction with respect to said member by said cam strips into different overlapping relations with respect to 10 plates 14, as determined by the amount of rotation of shaft 18 and the adjustment of cam strips 30, the amount of overlap between said plates produced by any predetermined amount of swinging movement of member 15 20 being variable as is manifest by bendably adjusting cam strips 30 through the instrumentality of screws 28, said cam strips causing plates 24 to be raised or lowered as desired during movement of said plates in a 25 relative angular direction by swinging movement of member 20 as is apparent. Thus, in instances where a plurality of condensers or other tuning units having the characteristics described in connection with the movable 30 parts thereof are connected together for collective operation by means of a single operator, such for example as shaft 18, cam strips 30 may be adjusted by means of screws 28 to cause all units to tune simultaneously and 35 accurately with each different wave length encountered during any continuous movement of the operator. Consequently, it is necessary to individually adjust the tuning units only once, since thereafter the cam 40 strips serve to produce the exact amount of overlap required between the plates of each unit during collective movements of the units to cause all units to tune simultaneously and accurately with each different wave length 45 encountered by any unit.

A simple yet effective manner of providing swivel connections between screws 28 and cam strips 30 consists in forming each screw with an annular groove and in forming 50 spaced pairs of fingers 34 along one edge of each cam strip adapted to be bent into said groove, and, if desired, a spring of any suitable material may be employed if found necessary or desirable to maintain rollers 32 at 55 all times in contact with cam strips 30.

In Figs. 4 to 7 I have illustrated an arrangement which differs from the arrangement of Figures 1 to 3 mainly in that instead of one set of plates of each condenser having two movements at an angle to one another, one set of plates has one movement and the other set the other movement, the results, however, being the same in each instance.

In the arrangement of Figures 4 to 7 an elongated bar 36 is mounted for longitudinal

movement in suitable spaced guide devices 38 secured to a suitable support such, for example, as a panel board 40, and rigidly secured to said bar at spaced points along the same is any desired plurality of sets of capacity 70 plates 42. A lateral extension 44 is formed on said bar adjacent to each set of plates 42 and each lateral extension has secured thereto a bar 46 in which is threaded a set of spaced screws 48 adjustably supporting, as in the 75 preferred form of my invention, a bendable cam strip 50. Each set of plates 42 has a companion set of plates 52 pivoted as at 54 to a suitable fixed support such, for example, as an adjacent guide device 38, and each set 80 of plates 52 carries a roller 56 riding upon its related cam strip 50, the result being that since the cam strips 50 move with the sets of plates 42 during shifting of bar 36, pivotal movements are imparted to plates 52 by said 85 cam strips during shifting of said bar to cause them to be raised or lowered during such shifting movements thereby to vary the area of overlap between related sets of plates 42, 52, so that all units will tune simultaneously and accurately with each different wave 90 length encountered by any unit during shifting of said bar.

I claim:

1. An electric condenser comprising an arm swingable about a fixed pivot, a movable plate pivotally connected with said arm, a stator plate with respect to which said first mentioned plate is movable into different overlapping relations by swinging movements of said arm, and means to produce pivotal movements of said first mentioned plate with respect to said arm during swinging movements of said arm. 95

2. An electric condenser comprising an arm swingable about a fixed pivot, a movable plate pivotally connected with said arm at a point spaced from the fixed pivot of said arm, a stator plate with respect to which said first mentioned plate is movable into different overlapping relations by swinging movements of said arm, a fixed cam, and a cam follower carried by said first mentioned plate cooperating with said cam to produce pivotal movements of said first mentioned plate during 100 swinging movements of said arm.

3. An electric condenser comprising an arm swingable about a fixed pivot, a movable plate pivotally connected with said arm at a point spaced from the fixed pivot of said arm, a stator plate with respect to which said first mentioned plate is movable into different overlapping relations by swinging movements of said arm, a cam, a cam follower carried by said first mentioned plate cooperating with said cam to produce pivotal movements of said first mentioned plate during swinging movements of said arm, and means supporting said cam operable to change the shape 110 thereof. 130

4. An electric condenser comprising a movable member, a plate pivotally connected with said member and whose pivot moves in a non-variable path during movement of the member, a stator plate with respect to which said first mentioned plate is movable into different overlapping relations by movement of the member, and means to produce pivotal movements of said first mentioned plate during movement of the member.
5. In mechanism of the class described consisting of a plurality of instrumentalities in co-operative relation and adapted to be adjusted from a single point of control, a main movable controlling element adapted to impart movement in equal degree to each of said instrumentalities, members comprised in each of said instrumentalities and connected with said main controlling element and adapted to be moved in equal degree by movements imparted therefrom, complementary elements cooperating with said movable elements and connections therefor, said connections comprising in each instance an individually adjustable cam track and a member cooperating therewith and adapted to impart independent compensatory movements to the complementary elements in an amount variably determined by the configuration of the cam track, substantially as described.

In testimony whereof I hereunto affix my signature.

DORSEY F. ASBURY.
